US00D636402S

(12) **United States Design Patent**
Vance et al.(10) **Patent No.:** US D636,402 S
(45) **Date of Patent:** ** Apr. 19, 2011(54) **PORTION OF A DISPLAY SCREEN WITH A
USER INTERFACE**(75) Inventors: **Michael Steffen Vance**, Kenmore, WA (US); **Jasdeep Singh Chugh**, Renton, WA (US); **Feridoon Malekzadeh**, Seattle, WA (US); **Valerie Lynn Goulart**, Seattle, WA (US); **Jupiter Macleod Barton**, Seattle, WA (US); **Jared T. Benson**, Pleasant Hill, CA (US); **Christian Robertson**, Concord, CA (US); **Shilpa R. Shah**, Oakland, CA (US); **Gabriel J. White**, San Francisco, CA (US)(73) Assignee: **T-Mobile USA, Inc.**, Bellevue, WA (US)(**) Term: **14 Years**(21) Appl. No.: **29/334,517**(22) Filed: **Mar. 27, 2009**(51) LOC (9) Cl. .... **32-00**(52) U.S. Cl. .... **D14/486**(58) Field of Classification Search D14/485-495;
715/700-867

Primary Examiner — Cathron C Brooks*Assistant Examiner* — Deanna Fluegeman(74) *Attorney, Agent, or Firm* — Knobbe Martens Olson & Bear LLP(57) **CLAIM**

The ornamental design for a portion of a display screen with a user interface, as shown and described.

DESCRIPTION

FIG. 1 is a front view of a portion of a display screen with a user interface showing the claimed design in accordance with a first embodiment; and,

FIG. 2 is a front view of a portion of a display screen with a user interface showing the claimed design in accordance with a second embodiment.

The portions of the user interface illustrated in broken lines form no part of the claimed design. The portion of the display screen is understood to be congruent with the shape of the user interface.
